PORTABLE FLUID APPLICATOR WITH
CONTROLLED FEED

Julian Judson Duncan, Garden City, N. Y., assignor to Western Electric Company, Incorporated, New York, N. Y., a corporation of New York

Application June 29, 1946, Serial No. 680,387

3 Claims. (Cl. 15—138)

1

This invention relates to fluid applicator devices and more particularly to an adjustable feed capillary wick oiler or lubricator.

In the lubrication of machine parts in assembly operations or in the maintenance of movable parts it is very desirable to have a manual lubricator that can be easily and quickly regulated to control the flow of lubricating oil so that very small or limited quantities of oil can be rapidly applied at designated points without diminution or increase in the flow at which the lubricator is adjusted. The difficulty with prior oilers is that too much oil is fed and applied to moving parts. The application of excess oil to a moving part results in the accumulation of dirt and interferes with efficient operation. This is particularly true where the parts are of fine construction and must be maintained in delicate balance and adjustment.

An object of the invention is to provide an adjustable feed capillary wick lubricator which is simple in construction and capable of accurate adjustment to control the flow of lubricating liquid therefrom.

Another object is to provide a pencil shaped oiler, light in weight, having a transparent oil storage reservoir, and easily manipulated to permit rapid and correct oiling of mechanisms.

With these and other objects in view, the invention comprises a pencil shaped oiler having a transparent plastic tubular oil reservoir from which oil is fed by capillary action through a felt wick compressed by a resilient rubber collet in a stuffing box which is adjustable to control the construction of the wick and hence the rate of feed of the oil therethrough.

Other objects and advantages will be apparent from the following detailed description when taken in conjunction with the accompanying drawing, wherein

Fig. 1 is a perspective view of an oiler or lubricator embodying the invention;

Fig. 2 is an enlarged longitudinal section thereof;

Fig. 3 is an enlarged view of the applicator end of the oiler, and

Fig. 4 is an enlarged view of the back end of the oiler.

Referring now to the drawings in which like reference numerals indicate similar parts throughout the several views, 10 designates a transparent oil reservoir which is made of any suitable plastic material such as polystyrene. Secured in and passing through and beyond the back end of the reservoir 10 is an aluminum dowel pin 11 which is used to prevent the oiler from

rolling off of a support when it is laid thereon by the user, and as a means for supporting the oiler in a vertical position while adjusting the capillary feed.

5 The inner front end of the reservoir 10 is threaded at 12 to receive a threaded reduced end of a knurled hollow aluminum bushing 13 having a central opening 14 through which a felt wick 15 passes. The bushing 13 is provided at its forward end with a reduced exteriorly threaded hollow portion 16 onto which is threaded an aluminum tubular shaped stuffing box or sleeve 17 having a central aperture 18 through which the wick 15 passes.

10 15 The stuffing box 17 has a chamber 19 concentric with the aperture 18 and in which is placed a compressible rubber collet 20 encircling the wick 15. The compressible collet 20 can be made of any suitable material such as natural rubber, neoprene, polybutadiene or any of the synthetic rubbers. Also threaded onto the reduced portion 16 of the bushing is knurled aluminum lock nut 21 which serves to lock the stuffing box 17 in an adjusted position.

20 25 The forward end of the central aperture 18 in the stuffing box 17 is threaded at 22 to receive the threaded end of a long hollow brass tip 23 which guides the wick 15 therethrough and holds its applicator end 24 in a desired position. This end of the wick is trimmed so that it extends about one-eighth of an inch beyond the metal tip 23.

30 35 In preparing the oiler for use, the transparent oil reservoir 10 is unscrewed from the knurled aluminum bushing 13 and the reservoir is about four-fifths filled with an oil of the desired quality. The oil reservoir 10 is then reassembled to the bushing 13 with the wick 15 positioned as shown in Figs. 1 and 2. The oiler or lubricator is then suspended by the dowel pin 11 with the applicator end 24 down until a drop of oil begins to form thereon. The stuffing box 17 is then tightened to compress and constrict the rubber collet 20 to a greater degree about the wick 15 until the formation of an oil drop stops or is very slow. The excess oil is then wiped from the applicator tip 24 of the wick and this applicator tip is then applied to the points on the apparatus to be lubricated. By observation it can be ascertained whether the stuffing box 17 should be tightened or loosened to deliver the lubricating oil slower or faster to the wick end 24. After the proper rate of oil feed has been determined, the stuffing box 17 is locked in adjusted position by tightening the knurled lock nut 21 thereagainst.

40 45 50 The lubricator or oiler is now used by lightly

pressing the felt tip 24 to the lubrication points of the apparatus or machine parts in rapid succession and the transparent reservoir 10 gives a visual indication at all times as to the quantity of oil therein.

It is to be understood that while the embodiment shown in the accompanying drawing is a preferred one, nevertheless the invention is susceptible of many different forms and is to be limited only by the scope of the appended claims.

What is claimed is:

1. An adjustable feed capillary wick oiler comprising a chambered transparent body having internal screw threads at an open end; a bushing threaded into the open end of the chambered body and having a threaded shank and a central bore extending through the bushing; a hollow sleeve threaded onto the shank of the bushing and adjustable on said shank; a resilient member positioned in the hollow of the sleeve and having a passageway of uniform diameter concentric with the central bore of the bushing and which passageway is adapted to be constricted between the sleeve and the bushing, said sleeve having a tapered end section; a long tubular tip removably attached to said end section; a wick having one end positioned within the chamber of the transparent body and extending through the bore in the bushing, the constricted passageway in the resilient member, the sleeve and through the long tubular tip so that the other end of the wick extends a predetermined distance beyond the end of the tip; and a locking nut threaded onto the shank of the bushing for cooperating with the sleeve to lock it in a predetermined position in constricting the passageway in the resilient member to constrict the wick to control the flow of oil from a supply in the chambered body to the end of the wick extending beyond the long tubular tip.

2. A fluid applicator comprising a wick; a chambered body having internal screw threads at an open end; a bushing having a threaded shank at one end and the other end thereof being threaded into said open end of the chambered body and having a central bore extending through the bushing, part of said bore being of approximately the same diameter as the wick and the remaining part being of larger diameter to form a second chamber for receiving the fluid; a hollow sleeve threaded onto said shank of said bushing and having a conical end section; an elongated hollow tip of approximately uniform diameter and secured to said end section; a resilient member positioned in the hollow portion of said sleeve and having a passageway axially aligned with the smaller portion of the bore of said bushing, said passageway being of uniform diameter for constricting the wick along the en-

tire length of the passageway; said wick extending from said chambered body through the larger portion of the bore of said bushing, the smaller portion of said bore, the passageway in said resilient member, through the sleeve, the elongated tip, and extending a predetermined distance beyond the outer end of the elongated tip; and a locking nut threaded onto the shank of the bushing for locking said sleeve in a predetermined position for constricting the passageway in the resilient member to constrict the wick to control the flow of fluid therethrough.

3. A flow metering device including a wick; a chambered body; a bushing threading into said chambered body and having a central bore; a hollow sleeve having an enlarged recess therein and a conical end; an elongated hollow tip of approximately uniform external diameter and secured to said end; said bushing having a shank extending a predetermined distance into said recess and forming a chamber within the sleeve; a resilient member having a passageway of uniform diameter in axial alignment with the central bore of the bushing and encircling a portion of the wick and occupying the entire space within the chamber of the sleeve; said wick extending from said chambered body through the central bore in the bushing, the passageway in the resilient member, the sleeve, the elongated tip, and extending a predetermined distance beyond the end of said tip; means for suspending the device in the vertical position while adjusting the sleeve to a predetermined position for constricting the passageway in the resilient member to constrict the wick to control the flow of fluid; and means for locking said sleeve in the predetermined position.
